(57) **CLAIM**

I claim the ornamental design for the strip lighting fixture, as shown and described.

DESCRIPTION

FIG. 1. is a bottom perspective view of the strip lighting fixture;

FIG. 2. is a top perspective view;

FIG. 3. is a bottom plan view of the strip lighting fixture;

FIG. 4. is a top plan view;

FIG. 5. is a side view of the strip lighting fixture;

FIG. 6. is an opposite side view;

FIG. 7. is an end elevation identifying the relationship between FIGS. 3, 4, 5, and 6;

FIG. 8. is an end perspective view of the strip lighting fixture;

FIG. 9. is an end elevation view of the strip lighting fixture illustrating an attached bulb receptacle; and,

FIG. 10. is an end perspective view of a variant of the strip lighting fixture depicted in FIGS. 1-9, including end caps, illustrating an attached end cap.

The broken lines shown on the drawings are for illustrative purposes only and form no part of the claimed design.
